UNITED STATES PATENT OFFICE

148,403

DESIGN FOR A BROOCH OR SIMILAR ARTICLE

Nicholas Barbieri, Providence, R. I.

Application December 26, 1946, Serial No. 135,765

Term of patent 14 years

(Cl. D45—19)

To all whom it may concern:

Be it known that I, Nicholas Barbieri, a citizen of the United States of America, residing at Providence, county of Providence, State of Rhode Island, have invented a new, original, and ornamental Design for a Brooch or Similar Article, of which the following is a specification, reference being had to the accompanying drawing, forming a part thereof.

Fig. 1 is a top plan view showing my new design for a brooch or similar article; and

Fig. 2 is an edge elevation thereof.

The dominant part of the design is shown in full lines.

I claim:

The ornamental design for a brooch or similar article, substantially as shown and described.

NICHOLAS BARBIERI.
